UNITED STATES PATENT OFFICE.

R. HALE SMITH, OF SPRINGFIELD, MASSACHUSETTS.

ELASTIC-FACED PRINTING-TYPE.

SPECIFICATION forming part of Letters Patent No. 326,599, dated September 22, 1885.

Application filed January 15, 1885. (No model.) Patented in England July 22, 1881, No. 3,191.

To all whom it may concern:

Be it known that I, R. HALE SMITH, of Springfield, in the county of Hampden and State of Massachusetts, have invented a new 5 and useful Improvement in Elastic-Faced Printing-Type, (for which Letters Patent were granted in England, dated July 22, 1881, No. 3,191,) of which the following is a specification and description.

10 My invention relates particularly to that class of printing type having a hard body and an elastic printing-face, and which are interchangeable and adapted to be set up in a form or stamp and used to print any desired matter by hand-pressure; and it consists of a metallic or hard printing-type of the well known ordinary form, and having a printing-character on one end made integral with the body, which character is covered around and upon 15 its printing-face with a coating of rubber or elastic compound vulcanized thereto.

In the drawings making a part of this specification, Figure I represents a plan view of a metallic printing-type having a printing-character (the letter *a*) of metal upon one end, and made integral with the body. Fig. II is a longitudinal sectional view, enlarged, of the same metallic printing-type, and prepared to receive the rubber coating vulcanized thereto, the face 20 of the printing-character being made rough for that purpose; and Fig. III is a sectional view, also enlarged, of the same metallic printing-type, and having its printing-character covered with the rubber coating vulcanized 25 thereof.

In the drawings, 2 represents the body of an ordinary printing-type, made, preferably, of the same metal of which the ordinary printing-types are made, and having upon one end 30 a printing-character (in this case the letter *a*) made of metal and integral with the body of the type, and all of the ordinary form used in printing. The face of the printing-character is preferably made somewhat rough by drawing a coarse file across it, or in any other convenient way, as shown in Fig. II, and the character is then covered with a coating of rubber, both upon its roughened face and also around the sides of the character and in all 35 its recesses and cavities, by vulcanizing the rubber placed between a matrix taken from a series of the type and a series of the type

themselves, and applying heat to both, with pressure applied to force the plastic rubber against and around the metallic printing-characters and into their recesses. In this way 55 the rubber is chemically and firmly united to all the parts of the printing-character of each particular type, and the whole series, being afterward separated or cut apart, may then be 60 used to set up any desired printing-matter in a stamp; and by applying any suitable ink to the printing-face of the rubber coating of the printing-characters fine and delicate impressions may be made therefrom by a very light 65 pressure of the hand.

I am aware that letters or characters have heretofore been made upon wooden blocks by first gluing or otherwise attaching a sheet of rubber cloth or other suitable rubber compound to one face of the block, and afterward carving a letter upon it, removing the rubber from all parts of the surface except that portion forming the printing-face of the letter; but it would of course be impossible to apply 70 75 rubber coating to small printing-type in that manner or by any such means, because it would be absolutely impossible to manipulate the rubber, either in cutting out the letters or in applying the sheets to the type, and produce 80 the same results obtained by vulcanizing the rubber to the type, as hereinbefore described; and wooden blocks prepared in that manner, and as set forth in the patent granted to P. Gfrorer, July 15, 1870, are only suited and 85 adapted to the coarsest class of printing—such, for example, as handbills, large posters, &c.—whereas printing-types having a thin coating of rubber vulcanized to their printing-characters are adapted to produce some 90 of the finest and most delicate printed matter, owing to the thinness and uniformity of the rubber when properly vulcanized to the printing-character of the type.

I am also aware that metallic blanks with 95 both ends made plane and flat have heretofore been used with a solid elastic printing-character vulcanized to one of its plane ends; but these printing-characters being elastic their whole depth from their printing-face to the 100 surface where they unite with the metal, their elastic quality renders them liable to bend over, some in one direction and some in another, and some flattening out more than oth-

ers, even in the same stamp and in the same impression. This is very hard to overcome in taking impressions from wholly elastic characters, from the fact that only a very slight pressure is required, and it is not always possible to apply the pressure in a perfectly-uniform manner by the hand.

The advantages of hard printing-type whose printing-characters are made integral with the body and are thinly coated with rubber vulcanized thereto are manifest and many. Any kind of suitable printing-ink may be applied thereto by which to make the impressions without any liability of disturbing or affecting the chemical union at the uniting surfaces of the elastic substance and the hard material forming the type, or causing the cushion to become loosened and disengaged therefrom; whereas the sheets secured to wooden blocks by some adhesive substance are liable to injury and will soon be rendered useless from the action of the ink upon the adhesive material, (especially if certain kinds of ink are used,) the rubber faces of the wooden letters thereby soon becoming loosened and detached.

In the elastic-faced printing-type herein described the printing-character itself, being made of a hard material and with a thin coating of rubber vulcanized thereto, is comparatively rigid and cannot bend or easily become

distorted in making an imprint, and they only yield to the hand-pressure sufficiently to insure a perfect contact of all parts of the printing-surface of the character with the paper, and a perfect and uniform impression, as well as a great uniformity of imprint in a series of impressions, is the result. I do not, therefore, claim any rubber sheets attached to the printing-face of wooden printing characters or blocks; neither do I claim a metallic body or blank having no printing-character and having a solid rubber or elastic printing-character vulcanized to one of its flat ends; but,

Having described my invention, what I do claim is—

An elastic-faced printing-type consisting of a hard-bodied printing-type whose printing-character is made integral with the body and having an elastic coating or cushion molded and vulcanized thereto, and whose said character projects or extends into said elastic coating or cushion to form an elastic-faced printing-character, and whereby the latter is supported and is secured firmly in place upon the type, substantially as described.

R. HALE SMITH.
